QUICK RELEASE ANCHOR
Stanley Joseph Meno, 110 Rathburn Road,
Toronto, Ontario, Canada
Filed Nov. 4, 1960, Ser. No. 67,340
4 Claims. (Cl. 114—208)

The invention relates to an anchor for small craft and the like which is adapted for dislodgement from underwater obstructions which may have fouled the same.

It is a general objective of the invention to provide an anchor of this type which has an adequate hold to withstand normal anchoring stresses but is adapted to release quickly when the recovery thereof is hindered by some underwater obstruction.

More specifically it is an object of the invention to provide an anchor having the foregoing advantages which is simple to operate and which is economical to manufacture.

A further and related objective is the provision of an anchor having the foregoing advantages which is easily stowable and occupies relatively little space.

The invention seeks to provide the foregoing and other advantages which will appear from the invention by the provision of anchor for small craft and the like adapted for dislodgement from underwater obstructions and comprising: an anchor shank; chain fastening means at one end of said shank; at least one anchor fluke at the other end of said shank; said fluke being swingably mounted for swinging between a set-up position extending at an angle from said shank and a quick release position aligned therewith; and interlock means for maintaining said fluke in its set-up position under normal anchoring stresses and being releasable to permit alignment into its quick release position in response to abnormal stresses.

A preferred embodiment of the invention will now be described with reference to the following drawings in which like reference devices refer to like parts thereof throughout the various views and diagrams and in which:

FIGURE 1 is an exploded view of the anchor according to the invention showing the flukes in their set-up position;

FIGURE 2 is an isometric view of the anchor of FIGURE 1 shown with the flukes in the quick release position;

FIGURE 3 is a section of a detail of the anchor of FIGURE 1 showing the flukes in the set-up position;

FIGURE 4 is a section of the interlock members shown in the section of FIGURE 3 corresponding to an intermediate position on the flukes;

FIGURE 5 is a schematic plan view of an anchor fluke at a stage in its construction; and,

FIGURE 6 is an exploded view of a further embodiment of the invention.

From FIGURES 1 to 4 it will be seen that the anchor 10 according to the invention comprises an anchor shank 11 having a ring 12 at one end thereof for fastening of the anchor chain (not shown), and a cross-member 13 extending from shank 11 intermediate its ends and normal thereto for ensuring positive engagement of the anchor 10 in known manner. At the other end of shank 11 tubular member 14 is welded substantially normal thereto for attachment of anchor flukes 15 as described below.

Each fluke 15 will be seen to be of channel-shaped cross-section along a substantial portion of its length, the web 16 thereof being extended to provide a blunt point 17 at the free end thereof. Apertures 18 are provided in the opposite flange portion 19 of each fluke 15 in registration with the opposite ends of tubular member 14, and bolt 20 is adapted to pass therethrough for swingably fastening flukes 15 on shank 11. Flukes 15 are thus rendered swingable between a set-up position extending from shank 11 at an angle thereto, corresponding to the

2

exploded view of FIGURE 1, and a quick release position aligned with shank 11 as shown in FIGURE 2.

In order to restrain swinging of flukes 15 beyond a predetermined critical angle shoulders 16a are formed on webs 16 oriented to engage shank 11 on opposite sides thereof when flukes 15 are in the set-up position.

In order to maintain flukes 15 in their set-up position interlock means are provided in the form of protruding male stud members 21 and female recess members 22 formed on respective flange portions 19 of flukes 15, for engagement with and disengagement from one another on swinging of flukes 15 into and out of the set-up position as aforesaid.

FIGURES 3 and 4 illustrate respectively the engaged and disengaged position of male and female members 21 and 22 and it will be understood that flange portions 19 of flukes 15 incorporate a certain degree of resilience permitting flexing towards and away from one another, male members 21 exerting a camming action forcing them apart for this purpose.

From the foregoing description it will be apparent that flukes 15 are particularly suitable for manufacture from sheet metal utilizing economical mass production techniques such as stamping out in "blank" form as shown in FIGURE 5 and subsequently folding into the channel shaped cross-section illustrated. In this connection it is noted that steel sheet of between 16 to 11 gauge has proved suitable for the production of anchor flukes 15 having adequate holding power for a small craft of from 15 to 20 feet in length.

An alternative embodiment of the invention is shown in FIGURE 6 which will be seen to comprise an anchor shank 23 having an aperture 24 formed in the end thereof for attachment of anchor flukes 25 thereto.

Anchor flukes 25 have a generally L-shaped cross-section formed of sheet metal and are provided with apertures 26 in their flange portions 27 in registration with aperture 24 in shank 23. Bolt 28 is provided for passing therethrough and swingably fastening the same for swinging between their set-up position corresponding to the position of flukes 25 shown in FIGURE 6 and their quick release position corresponding to the position of anchor flukes 15 shown in FIGURE 2.

In order to maintain anchor flukes 25 in their set-up position interlock means are provided in the form of apertures 29 adapted and oriented for alignment when in the set-up position, and shear pin 30 passing therethrough and locking flukes 25 in their set-up position under normal anchoring stresses but being designed to fracture under abnormal stresses.

In operation anchor flukes 15 are swung about bolt 20 by hand into their set-up position, male stud members 21 causing flange portions 19 to flex away from one another and snapping firmly into female recess members 22 when they are brought into registration with one another, the inherent resilience of flange portions 19 locking them in this position and preventing inadvertent disengagement thereof and with shoulders 16a of webs 16 engaging opposite sides of shank 11 and limiting movement of flukes 15 relative thereto.

Anchor 10 may then be lowered in the normal way, cross-member 13 forcing one or other of flukes 15 to bite into the sea or river bed in known manner. It will be understood that the grip of male and female members 21 and 22 is adequate to enable anchor 10 to be used in this way, the strain on anchor 10 in any event being generally reduced by the weight of the anchor chain or rope (not shown) which, in the majority of cases, will measure at least three times the depth of the water in which the craft (not shown) is lying, thus permitting the formation of a "catenary" of chain between itself and anchor 10.

When it is desired to recover or "weigh" anchor 10 the

chain is shortened until the craft lies directly over anchor 10 at which time one or other of flukes 15 will generally have twisted loose from the sea bed permitting anchor 10 to be hauled in.

In the event that a fluke 15 is caught around some underwater obstruction or is usually securely lodged in the sea bed a sharp pull vertically upwards on the anchor chain will generally be sufficient to force male and female members 21 and 22 to become disengaged thus permitting flukes 15 to swing downwardly into their quick release position aligned with shank 11 and enabling anchor 10 to be readily freed from the obstruction and recovered.

Where larger craft are concerned anchor 10 may be of such size as to render this type of manipulation impractical and in such cases male and female members 21 and 22 can generally be disengaged by motoring ahead directly over and past the anchor 10 at a suitable speed.

The foregoing is a description of a preferred embodiment of the invention and is here made by way of example only and the invention is not limited to the specific features shown but contemplates all such variations as come within the spirit of the invention as defined by the following claims.

What I claim is:

1. An anchor for small craft and the like adapted for dislodgment from underwater obstructions and comprising: an anchor shank; line fastening means at one end of said shank; a pair of anchor flukes at the other end of said shank; said flukes being swingably mounted for swinging between a set-up position extending at an angle from said shank end on opposite sides thereof and a quick-release position substantially aligned therewith; and male and female interlocking members formed on said flukes, a male member of one said fluke being aligned for engagement with a female member of the other said fluke when said flukes are in their set-up position and being releasable therefrom in response to abnormal stresses to permit alignment of said flukes in their quick-release position.

2. An anchor for small craft and the like adapted for

dislodgement from underwater obstructions as claimed in claim 1 including a cross-member extending from said shank intermediate its ends and substantially normal thereto and to the axis of said flukes in their set-up position.

5. An anchor for small craft and the like adapted for dislodgement from underwater obstructions as claimed in claim 1 including a tubular member fastened to said anchor shank across the end thereof adjacent said flukes and substantially normal thereto; apertures formed in said 10 flukes in registration with the axis of said tubular member; and fastening means passing therethrough for swingably mounting said anchor flukes as aforesaid.
4. An anchor for small craft and the like adapted for dislodgement from underwater obstructions as claimed in claim 1 wherein each said anchor fluke is formed of sheet metal folded into a channel cross-section; one end of each said fluke being formed by an endwise extension of the web of said channel and constituting a blunt point therefor; the other said end of each said fluke being provided with one pair of aligned apertures in respective flange portions of said channel for fastening thereof to said anchor shank; and being further provided with male and female interlock members joined in respective flange portions, said members being spaced from said apertures 25 aforesaid and aligned with one another; the male member of one said fluke being engageable with and disengageable from the female member of the other said fluke by flexing of said flange portions thereof in response to swinging movement of at least one of said flukes about 30 the axis of its respective said apertures.
